DIAL OPERATED TYPEWRITER

John W. Ehemann, Chicago, Ill., assignor to Dialrite
Associates, Battle Creek, Mich.

Application March 2, 1953, Serial No. 23,850

Term of patent 14 years

(Cl. D64—11)

I claim:

The ornamental design for a dial operated typewriter, substantially as shown.
